GEORGE Z. SMITH AND EDWIN B. HERBERT, OF FOLLANSBEE, WEST VIRGINIA.

FEEDER FOR PULVERIZED COAL.

Application filed November 13, 1920. Serial No. 423,891.

To all whom it may concern:

Be it known that we, GEORGE Z. SMITH and EDWIN B. HERBERT, citizens of the United States of America, and residents of 5 Follansbee, county of Brooke, and State of West Virginia, have invented certain new and useful Improvements in Feeders for Pulverized Coal, of which the following is a specification.

10 This invention relates to feeding devices for pulverized material and involves more especially the provision of a pulverized fuel feeder for delivering fuel to a furnace.

In one form of device used extensively in 15 practice for feeding pulverized fuel, for instance, to a furnace, a screw is employed for conveying the fuel from a supply bin to the burner tube of the furnace, through a feed pipe in which the screw is mounted for 20 rotation, the fuel dropping by gravity from the feed pipe through a suitable connection to the burner tube from which the fuel is injected into the furnace by means of a blast of air. The screw is connected to driving means, usually a motor, and the amount 25 of fuel delivered by the screw in a given time depends upon the speed at which it is driven by the motor. In order that the amount of fuel delivered may be regulated 30 in accordance with the requirements, it is customary to provide a variable speed direct current motor; or when the use of such a motor is not feasible, as where the only available source of electrical energy is alternating current, to employ a constant speed 35 motor with speed changing devices interposed between the motor and the screw shaft for varying the speed at which the latter is to be driven. This form of fuel feeder, 40 therefore, has the disadvantage of depending for its driving means upon a motor of limited application, and, in the alternative, speed changing devices such as a system of gears which are more or less complicated in 45 construction and expensive to install.

Contrasted with prior devices, the pulverized fuel feeder constructed in accordance with this invention may be regulated to deliver the fuel at a rate which may be adjusted 50 by the attendant in exact accordance with the amount of fuel required in a given time while the feeding devices of the apparatus are at all times driven at constant speed. Unlike prior mechanisms wherein a screw 55 is depended upon to propel the fuel to the point of delivery, in accordance with which

arrangement the amount of fuel delivered will be governed by the speed of rotation of the screw, the feeding devices of the apparatus of this invention serve merely to 60 prepare the fuel for delivery to a casing and to produce a steady uninterrupted flow of fuel into the casing. The rate at which the fuel is fed to the casing is controlled by a valve situated in the inlet opening of the 65 casing for fuel. Manually adjustable means are provided whereby this valve may be set to increase or decrease the rate of flow as desired; also means for discharging the fuel from the casing through a feed pipe to the 70 point of delivery.

Preferably the fuel is supplied to the casing from a receptacle which is situated at a higher level than the casing so that the fuel will gravitate to the latter, and in this case 75 the feeding devices of the apparatus assist gravity in producing and maintaining a steady uniform flow of pulverized fuel from the receptacle to the casing at a rate dependent upon the valve setting.

In the preferred construction of the feeding devices contained within the apparatus, propeller blades are included for creating a constant upheaval of the fuel as it descends from the receptacle, thus keeping the 85 fuel in a state of mobility in preparation for its delivery to the casing so that its flow through the inlet opening thereof, as regulated by the valve, will be continuous and at a uniform rate for a given valve setting. 90 These blades are provided with notches through which the fuel falls by gravity to the inlet opening of the casing.

The invention is illustrated in the accompanying drawings, in which— 95

Figure 1 is a sectional elevation of the invention;

Figure 2 is an enlarged section on line 2—2, Fig. 1;

Figure 3 is a top plan view of the feeder 100 casing with the working parts removed therefrom; and—

Figure 4 is a perspective view of the fuel-lifting agitator bar.

Referring to said drawings, in which like 105 designating characters distinguish like parts throughout the several views—

1 indicates a hopper-like supply bin or reservoir for powdered coal. Attached thereto in underlying relation to its mouth 110 is a basin-like receptacle 2 forming a continuation of the hopper 1 and constituting

the bottom portion thereof and which is provided with a central bottom opening 3. Fitted within said opening and projecting upwardly therethrough into the interior of said basin is the upper cylindrical end portion of a casing 4, an external annular flange 5 formed upon said casing being attached, as by means of bolts 6, to the adjacent opening-defining edge of said basin.

10 The casing 4 has located therein at a suitable distance from its upper end an internal annular flange 7 upon which rests a centrally apertured plate 8 constituting a seat for a valve 9 of inverted-cone shape carried by a vertically disposed rotary shaft 10. Said valve seat 8 has its inner peripheral edge upwardly beveled, and the valve 9 is adjustable with respect to the edge for regulating the extent of the valve opening and thus the flow of powdered fuel to the underlying chamber 11 formed by the lower end of the casing.

15 The shaft 10 has the said valve 9 formed thereon or attached thereto intermediate its ends. That portion of the shaft located above the valve projects somewhat above the upper end of the casing 4 and carries a horizontally disposed bar 12 having a length approximating the diameter of the bin mouth. This bar rotates with the shaft and acts to stir or agitate the powdered coal for preventing "arching" or "hanging" of the latter about the upper end of the casing. To facilitate the lifting of the pulverized fuel the agitator bar has its opposite end portions 12^a of beveled form, the bevel on one end being oppositely inclined to that on the other end.

20 Carried by the shaft 10 and extending from a point closely underlying the agitator bar 12 to a point closely overlying the valve 9 are one or more spiral propeller blades 13 by which, when the shaft is rotated in a forward direction, the coal in the upper end of the casing is elevated and kept in a constant state of upheaval, and the fuel is thereby rendered mobile so that it will flow steadily and uniformly through the valve opening in the lower chamber of the casing at a rate depending upon the setting of the valve. Notches 14 or other suitable forms of openings or recesses are provided at suitable intervals in the propeller blades, and these afford passageways through which the fuel is permitted to pass to lower levels by gravity. In the nearly-seated position of the valve the lower inclined ends of the blades closely overlie the valve seat 8 and constitute scrapers by which the coal is largely prevented from collecting upon the seat. As means for preventing collection of coal upon the seat when the valve is elevated to a considerable height, one or more pins 15 are mounted loosely in vertical positions in the outer edge portions of the pro-

25 pellers. These pins are provided with heads 16 which, due to the loose character of their mountings, permanently remain by force of gravity in direct engagement with the upper surface of the valve seat and so act to scrape the seat as they are advanced over the latter through rotation of the shaft.

Opening outward through the casing 4 from the chamber 11 is a passage 17 through which the pulverized fuel delivered past the valve 9 is directed to the furnace, the passage being adapted to have a feed pipe leading to the furnace coupled thereto. Directed into the chamber 11 at the side opposite the passage 17 so as to occupy a position in direct alinement with the center of the latter is a nozzle 18 through which a continuous blast of air is directed for carrying the fuel to the furnace. The center line of the nozzle and the passage 17 is located laterally with respect to the shaft 10 so that the latter will in no wise interfere with the delivery of the air blast for directing the fuel through the passage.

30 The shaft 10 extends downward through an opening provided therefor in the bottom of the casing 4, a suitable gland, as 19, being provided to prevent leakage. The shaft is mounted in a bearing 20 located at a suitable distance below the casing 4, this bearing being herein shown as carried by a bracket arm 21 which depends from one side of the basin 2. Also formed on the arm 21 at a suitable point is a bearing 22 in which is journaled a drive-shaft 23 designed to be connected to a constant speed motor, as through a belt operating on a pulley or belt wheel 24 carried by the outer end of said drive-shaft. A bevel pinion 25 carried on the inner end of the drive-shaft is operatively engaged with a bevel-gear 26 carried by the shaft 10 in a position directly overlying the bearing 20.

35 The bevel gear 26 is maintained against rotation on the shaft 10 by means of a key 27 which is loosely fitted in ways 28 and 29 provided therefor in the shaft and the hub of said gear, respectively. The way 28 is of such greater length than the key that any desired vertical adjustment 40 of the shaft 10 may be effected. A yoke 30 which is fitted into an annular groove or channel 31 in the lower part of the hub of the bevel gear, and which is rigidly attached to the upper end of the bearing 20, 45 as by means of screws 41, serves to maintain the bevel gear against vertical movement.

45 A collar 32 adjustably mounted on the shaft 10 intermediate the gear 26 and the bottom of the casing 4 is designed for adjustment to limit the extent of vertical valve-opening movement of said shaft.

50 The lower end of the shaft 10 is formed with a short reduced neck 33 terminated by

a head 34, the latter being also reduced with respect to the diameter of the shaft. Loosely fitted in partially embracing relation to the head 34 and the neck 33 is a yoke-like portion 35^a formed on a head 35 carried by the upper end of a screw 36 which is directed vertically upward through a fixed bottom end wall 37 formed on the bearing 20. The head 35 constitutes a seat upon which the shaft 10 rests and with respect to which the shaft is freely rotatable. Fixed upon the outer end of the screw 36 is a handwheel 42 by means of which the screw may be rotated for elevating and lowering the shaft for adjusting the valve 9 with respect to its seat 8. A nut 38, preferably provided with a handle 39 whereby it may be conveniently rotated, is provided for locking the screw in adjusted position.

While the screw 36, as described, constitutes an operative means for shifting the position of the shaft in a longitudinal direction to adjust the valve, it will be understood that this is merely illustrative, it being obvious that various other devices for effecting such shifting might readily be substituted therefor.

To provide for adjustment of the casing 4 so that the discharge passage 17 may face in any direction most suitable for coupling to a pipe or pipes leading to the furnace, the openings in the flange 5 for the attaching bolts 6 are in the form of arcuate slots, as shown at 40 in Fig. 3.

The valve 9 is preferably formed on its under, or inclined, sides with one or more radial arms or blades 43 of approximately triangular form, as shown, these blades being designed to act within the opening defined by the flange 5 for preventing undue collection of fuel in and about the opening.

In practice, the rotating shaft 10 is adjusted vertically to properly position the valve 9 with respect to its seat for permitting of the passage thereby of the powdered fuel in the quantity required for feeding the furnace. The agitator bar 12 carried by the upper end of the rotating shaft acts to produce a constant upheaval of the fuel at and adjacent to the mouth of the bin, whereby "arching" or "hanging" of the fuel is effectually prevented and a constant supply of fuel to the interior of the upper part of the casing 4 is consequently assured. The fuel so supplied to the upper part of the casing is subjected by the propeller blades 13 to a constant upheaval which prevents all tendency of the fuel to pack and thus render feeding past the valve more or less irregular or spasmodic. The fuel so acted upon by the blades drops by gravity past the edges of said blades and through the openings or notches 14 thereof, in a steady uniform flow at the rate fixed by the valve setting while the feeding devices including the agitator

bars and propeller blades are rotated at constant speed, and collection of fuel upon the horizontal ledge of the valve seat 8 is prevented by the constantly acting scraping-heads 16 of the pins 15. Having passed to the chamber 11 in the lower part of the casing, the fuel is acted upon by the air blast issuing from the nozzle 18 and is thereby directed outward to the furnace through the passage 17 in a stream of uniform or unvarying volume. As is obvious, this volume may be instantly diminished or increased by adjustment of the valve toward or away from its seat while the feeding devices are driven at constant speed.

What is claimed is—

1. In a pulverized fuel feeder, a casing having an inlet opening, a receptacle situated above the casing for supplying fuel to the casing through said inlet, a shaft extending through the casing carrying a valve for controlling said opening and carrying feeding devices including spiral propeller blades situated above the inlet opening arranged to elevate the fuel and to keep it in a constant state of upheaval, a motor for driving said shaft carrying said feeding devices at constant speed producing, in conjunction with the action of gravity, a steady flow of fuel from the receptacle to the casing at a rate depending upon the setting of the valve, and means for discharging the fuel from the casing.
2. In a pulverized fuel feeder, a casing having an inlet opening, a valve controlling said opening, a receptacle for supplying the fuel to the casing through said inlet, means for regulating said valve, feeding devices interposed between the supply receptacle and the casing, and means for driving said feeding devices at constant speed, said feeding devices including propeller blades having notches therein and being constructed and arranged to produce, when driven at constant speed, and in conjunction with the action of gravity, a steady flow of fuel from the receptacle and downwardly through said notches to the casing at a rate depending upon the setting of said valve, and means for discharging the fuel from the casing.
3. In a pulverized fuel feeder, a casing having an inlet opening, a valve controlling said opening, a receptacle situated above the casing for supplying fuel thereto through said inlet, means for regulating said valve, feeding devices interposed between the supply receptacle and the casing, and means for driving said feeding devices at constant speed, said devices including propeller blades mounted above the inlet opening of the casing, and stirring rods loosely mounted in said propeller blades which are normally in position, by action of gravity, to sweep the fuel collecting about said inlet opening as it is fed from said fuel receptacle to the

casing by action of said feeding devices assisted by gravity in a steady flow and at a rate depending upon the setting of said valve, and means for discharging the fuel from the casing.

4. In a pulverized fuel feeder, a casing having an inlet opening, a receptacle for supplying fuel thereto through said inlet, a shaft extending through the casing carrying a valve for controlling said opening and feeding devices comprising propeller blades mounted above the inlet opening of the casing, stirring rods loosely mounted in said blades and an agitating bar having triangular shaped blades sloping in the direction of rotation of the shaft and situated in said fuel receptacle, a motor for driving said shaft at a constant speed, and means for discharging the fuel from the casing as it is fed thereto by action of said feeding devices assisted by gravity in a steady flow depending upon the setting of said valve, and means for moving said shaft longitudinally to regulate said valve.
5. In a pulverized fuel feeder, a casing having an inlet opening, a valve controlling said opening, a receptacle for supplying the

fuel to the casing through said inlet, means for regulating said valve, feeding devices interposed between the supply receptacle and the casing, means for driving said feeding devices at a constant speed, said devices being constructed and arranged to produce, when driven at constant speed, a steady flow of fuel from the receptacle to the casing at a rate depending upon the setting of said valve, and said casing having an outlet opening for fuel and an inlet opening for air under pressure, said openings being in alignment and the axial line thereof being situated to one side of the inlet opening of the casing for fuel, whereby the flow of fuel into the casing will proceed without interference by contact with the air blast, and will be assisted by the induction action resulting in the casing from said air blast.

In testimony whereof we affix our signatures in presence of two witnesses.
